UNITED STATES PATENT OFFICE.

HARRY B. MURDOCK, OF NEW YORK, N. Y., ASSIGNOR TO VAN DERBECK, SAYERS, MURDOCK CO. INC., OF NEW YORK, N. Y., A CORPORATION OF NEW YORK.

PERMUTATION ELECTRIC SWITCH.

1,183,026.

Specification of Letters Patent.

Patented May 16, 1916.

Application filed June 12, 1915. Serial No. 33,635.

To all whom it may concern:

Be it known that I, HARRY B. MURDOCK, a citizen of the United States of America, residing in the city of New York, borough of Manhattan, county and State of New York, have invented certain new and useful Improvements in Permutation Electric Switches, of which the following is a specification.

10 *This invention relates to safety controlling devices for electric circuits, and has for an object to provide an electric switch which is capable of closing the circuit only when set according to a permutation.*

15 *The mechanism is peculiarly adapted for use in connection with the ignition system of an internal combustion engine whereby the circuit may be broken when desired, and which circuit can only be closed again by 20 one knowing the combination of numbers or the permutation number or word.*

25 *In the drawings accompanying this specification, one practicable embodiment of a form of my invention is illustrated.*

30 *In these drawings, Figure 1 is a face view of the switch and a diagrammatic representation of an electric circuit. Fig. 2 is a section of the device shown in Fig. 1, taken on a plane at about the line 2--2 of Fig. 1, and Fig. 3 is a section taken on a plane transverse to the plane of Fig. 2, and at 35 about the line 3--3 in Fig. 2, the pivotal ends of the levers being shown in different planes for the purpose of illustrating the insulation block which supports these levers.*

35 *The form of the invention herein shown, and which may be regarded as illustrative of the invention, is designed for use in connection with an automobile or motor boat, 40 and is designed in such manner that it may be secured in some suitable position for the convenient actuation of the operator, as, for instance, on the cowl dash-board of an automobile. The back-plate 1 of the casing 45 is made of some suitable material, whereby it may be readily installed in position. Fiber is a convenient material for this purpose, since the leading-in wires may be brought into the mechanism from any convenient portion of this base or back-plate. The outer casing 2 is shown as being of circular formation and having suitable connection with the base or back-plate 1. In the present illustration these parts are con-*

nected together by a tight fit, a suitable rabbit being formed on the base plate. The outer edge of the side casing is shown provided with an extending flange 3 for giving strength and rigidity to the parts, and also for the purpose of ornamentation. 55

60 *The mechanism comprises a plurality of switches, each switch being provided with a lever and a series of contact points, which levers and a contact selected from each series are connected together in series in such manner that the circuit may only be closed by bringing each lever into engagement with the selected contact point. A ring of insulation 4 is shown located within the casing 2 and secured thereto in some 70 suitable manner, as for instance by means of screws. In this ring there are mounted the series of contact points designated without preference by the reference character 5 in Fig. 2. In Figs. 1 and 3 the series of 75 contact points are designated by reference characters 5^a, 5^b, 5^c and 5^d, respectively. The face-plate 6 is secured in the casing outwardly or forwardly of the insulation ring 4 and the contact points 5. In the present 80 illustration the face-plate is shown provided with a plurality of radially extending arms 7, which are shown bent transversely and backwardly at 7' and are of sufficient length to rest against the insulation ring 4 for properly positioning the face-plate relatively to such ring and the parts carried by these two elements respectively. The feet 7' are secured to the casing in some suitable manner, as for instance by means of screws. The 85 face-plate is provided with a series of indices for the contact points, these respective series being indicated by the reference characters 8^a, 8^b, 8^c, 8^d. These index numbers are so located on the face-plate that they 90 indicate the position of the levers which 95 coöperate with the contact points. Such levers are indicated in the drawings by the reference characters 9^a, 9^b, 9^c, 9^d. The pivots for the levers and the major portion of 100 each is shown located inwardly or rearwardly of the face-plate and guarded and concealed thereby. A block of insulation 10 is shown carried by the rear of the face-plate and suitably secured thereto by screws 105 20. This insulation is for the purpose of receiving the pivot posts 11 of the levers 9, and for insulating these one from the other*

and from the casing and other portions of the mechanism with which they are not intended to make circuit. These pivot posts 11 are shown located at equal distances from the center of the casing, and are disposed at angular distances of 90° apart. The path of movement of the outer end of the lever is, therefore, eccentric to the casing 2. The arms 7 which support the face-plate form the limits of the path of movement of each lever, the levers being provided with up-turned portions 91 which traverse the space 12 between the arms 7, the edge of the face-plate and the side of the casing. Each lever arm is also provided with an index pointer 92 which extends over the front face of the face-plate and is located in position to register with the index provided therefor, and indicate which of the switch points is covered by the lever at any particular time. For convenience of operation each switch lever is provided with an actuating handle 93. In the present illustration the contact points are shown in the form of bolts, each having a nut 51 for holding it in proper position in the insulation ring 4, and a nut 52 which may be backed off for the insertion of the connecting wires. The lever posts are shown in the form of screws capable of actuation by means of a screw driver for permitting the connection of the wires.

An electric conductor is shown detachably attached to a selected point of each said series of contact points. These conductors in the illustration are suitable wires, and the cover plate 6 acts as a covering means for obscuring and protecting the conductors where these are attached to the contact points. Some of the switch levers are shown in the illustration detachably attached to some of the conductors above mentioned, and other of the switch levers detachably connected together. These connections are all selective and an illustrative example of a selected series of connections follows.

A source of electrical current is shown in conventional form at 13, one lead line 14 of which is shown entering the casing and connected to one of the contact points. In the present showing it is connected to the contact point in the series 5^a which corresponds to index number 8 in the index series 8^a. The other lead wire 15 is shown having wires 151, 152, extending to and returning from some electrical apparatus, the circuit of which is controlled by the mechanism herein illustrated. This controlled mechanism may be of any nature whatsoever. The lead line 15 is shown connected to the contact point of the series 5^a, which corresponds to the index figure 4 of the index series 8^a. A wire 16 is shown connecting the pivot posts 11 of the switch lever arms 9^a and 3^a. A wire 17 is shown connecting the pivot post 11 of the switch lever arm 8^a with the contact point of the series of contact points 5^a, which corresponds to figure 6 of the index series 8^a. And the pivot post 11 of the switch lever arm 9^a is connected by means of a wire 18 to the contact point of the series 7^a which corresponds to figure 7 of the index series 8^a.

With the parts in the figure 1 position, and the wiring as represented in the diagram illustrated therein, the electric circuit is open. The permutation number, reading indices clockwise, is 7—8—4—6. When the operator desires to close the circuit it will be necessary for him to move those levers which are out of contact with the selected contact points, into engagement therewith. He, knowing the permutation, will move the lever 9^a one point forward, the lever 8^a two points forward, and the lever 6^a two points forward. The lever 8^a being in proper position, he will not move the same. This, therefore, brings the levers into the previously arranged permutation or combination, and so far as this switch is concerned, the electric circuit is closed. Then, whatever other manipulations are necessary or desirable will be performed in the circuit to open and close the same as occasion may demand. When the operator of the mechanism operated by the circuit controlled by this device wishes to leave such mechanism in a place where it is liable to be interfered with by an unauthorized person, he moves one or more of the switch levers from its circuit closing position. If a person unacquainted with the permutation attempts to re-set the switches, he is as liable to move the switch which is closing its circuit to an open position, as he is to move the lever which is out of contact with the switch point in circuit.

The operator may change the permutation as often as he desires, by merely removing the casing 2 from the back-plate 1 and changing the connections of one or more of the connecting wires; that is, shifting its connection from one to another of the contact points 5 of the series to which such wire leads.

Although but one form of the invention has been shown in the drawings, it will be apparent that this is illustrative of the invention and that changes may be made within the scope of the claims without departing from the spirit of the invention.

What I claim is—

1. A permutation electric switch comprising a casing, a face plate having a series of outwardly extending arms, said arms being carried by the casing and there being a space between the edge of the plate and the casing between adjacent arms, a series of switch levers pivoted rearwardly of the face plate and having portions respectively disposed in the said spaces and portions constituting index pointers, the face of the plate having

an index for each said pointer, and a series of contact points disposed rearwardly of the plate for each switch lever.

2. A permutation electric switch comprising a circular casing, a face plate having a series of outwardly extending arms, said arms being carried by the casing and there being a space between the edge of the plate and the casing between adjacent arms, a series of switch levers pivoted rearwardly of the face plate and having portions respectively disposed in the said spaces and portions projecting over the face of the plate and constituting index pointers, the face of the plate having an index for each said pointer, and a series of contact points disposed rearwardly of the plate for each switch lever.

3. A permutation electric switch comprising a circular casing, a face plate having a series of outwardly extending arms, said arms being carried by the casing and there being a space between the edge of the plate and the casing between adjacent arms, a series of switch levers pivoted rearwardly of the face plate between the casing and its center and having portions respectively disposed in the said spaces and portions constituting index pointers, the face of the plate having an index for each said pointer, a ring of insulation carried by the casing rearwardly of the plate, and a series of contact points carried by the ring for each switch lever.

HARRY B. MURDOCK.
